[57] CLAIM

The ornamental design for a blank for cup with top closure, as shown and described.

DESCRIPTION

FIG. 1 is a plan view of one face of the blank for cup with top closure showing my new design, the plan view of the opposite face is a mirror image thereof;

FIG. 2 is a top edge view thereof;

FIG. 3 is a bottom edge view thereof;

FIG. 4 is a left side edge view thereof; and,

FIG. 5 is a right side elevation view thereof.
